UNITED STATES PATENT OFFICE.

ISIDOR KITSEE, OF PHILADELPHIA, PENNSYLVANIA.

TELEGRAPHY.

No. 889,792.

Specification of Letters Patent.

Patented June 2, 1908.

Application filed December 21, 1906. Serial No. 348,977.

To all whom it may concern:

Be it known that I, ISIDOR KITSEE, citizen of the United States, residing at Philadelphia, in the county of Philadelphia and 5 State of Pennsylvania, have invented certain new and useful Improvements in Telegraphy, of which the following is a specification.

My invention relates to an improvement 10 in telegraphy and has more special reference to the receiving device.

I have found that if rapidly recurring or 15 alternating impulses, such for instance as are produced with the aid of an induction coil or converter, are transmitted over a circuit, one terminal of which consists of aluminium—preferably with a heavy film of oxid on the surface—and the other terminal consists of a non-oxidized material, such for 20 instance as platinum, and a shunt is established around these terminals, impulses of one direction will flow through the circuit and the impulses of opposite direction will 25 flow through the shunt.

In my experiments, I had recourse besides 30 others to an adjustable device consisting of a primary and secondary, the primary was, in some of the experiments, connected only to one dry cell, and with the aid of an interrupter, the circuit of the primary was rapidly 35 made and broken. In the secondary, I had an arrangement substantially such as described, that is, an aluminium pencil provided on its surface with a heavy oxid slightly touching a platinum pencil. In the shunt 40 around these two pencils, I had a telephonic receiver and when the device was put in operation, the impulses in the receiver were such as are produced in the same through the making and breaking of a circuit, thus 45 showing that a straight pulsatory current was flowing through the phone. In some of the experiments, I substituted for the phone a galvanometer of the D'Arsonval type, and the needle was deflected in the same manner 50 as if a straight current was passing through the coil. To find out how far impedance coils would retard the flow of the current in the shunt and force both set of impulses to flow through the straight circuit, I had recourse to impedance coils and connected the 55 same in series with the galvanometer. In one of the experiments, I placed in the shunt circuit in connection with the galvanometer on each side of the system, two impedance coils, each five thousand ohms and forty four henries and still the needle gave a large de-

flection. When air-gaps were introduced in the circuit, in a manner so that only a silent discharge was produced between two parts of the circuit, the needle gave still a comparatively large deflection. With one dry cell, 60 the needle, without any air-gaps, gave over ten deflections with the impedances in the circuit.

Having had occasion to make use of the 65 well known siphon recorder of Lord Kelvin for other purposes and being aware that to work this instrument, a current giving less than ten deflections is able to operate the same, I inserted the rectangular coil of the 70 recorder in the shunt and made the primary circuit with the aid of a telegraphic transmitting key, having the same closed for a short period to denote a dot and a longer period to denote a dash, the vibratory device 75 being always in the shunt, and the siphon recording on the paper a line, substantially as illustrated in Figure 2; that is, the siphon was deflected to one side of an imaginary zero line for a short time when a dot was 80 transmitted and for a longer time when a dash was transmitted and recorded a short curve for a dot and a longer curve for a dash. In looking carefully over this record with a magnifying glass, it was found that the 85 curved line was in reality composed of a large number of vibratory lines, thus showing that in reality the current was not an uninterrupted straight current, but was composed of a great number of impulses flowing in the 90 same direction, the time elapsing between one impulse and the succeeding impulse being too short to allow the siphon to return to its zero position.

Coming now to the practical application 95 of this invention and more especially to its application in wireless telegraphy, I produced arrangements substantially as are illustrated in the accompanying drawing, and I received electric waves, such as are 100 produced through oscillations or with the aid of an inductorium, with the aid of a telephonic receiver, with the aid of a galvanometer and also with the aid of a siphon recorder. To distinguish the arrangement placed in the 105 circuit from other arrangements, I call the same a dry asymmetric cell.

Referring to the drawing, Fig. 1 is a diagrammatic view of part of a circuit including a dry asymmetric cell and provided 110 with a receiving arrangement. Fig. 2 is a partially diagrammatic and partially per-

spective view of a circuit including a dry asymmetric cell and a siphon recorder as receiver. Fig. 3 is a diagrammatic view illustrating part of a circuit with two branches, 5 each branch provided with a dry asymmetric cell. Fig. 4 is a sectional view of one of the plates as illustrated in Fig. 2.

1 is the part of the circuit adapted to be connected to the aerial wire and 2 the circuit 10 connected to the ground; 3 is the asymmetric cell as an entirety, of which 4 is one electrode, here representing an aluminium electrode and 5 is the opposite electrode. These electrodes may be in loose contact with each 15 other, or may be separated from each other by a very slight air-gap. 6 and 7 are the shunt wires; 8 is a telephonic transmitter and 9 a siphon recorder.

In Fig. 3, 10 and 11 are the two branches 20 of the receiving circuit, the branch 10 comprising the dry asymmetric cell 3 and consisting of the electrodes 4 and 5; the branch 11 comprising the dry asymmetric cell 12 and comprising the electrodes 13 and 14. When, 25 with this arrangement, aluminium and platinum electrodes are employed, the upper electrode should in one branch consist of aluminium and in the other branch of platinum; and the lower electrode should consist in the 30 first branch of platinum and in the second branch of aluminium.

In practicing this, my invention, in a wireless system of comparatively long distance, it is best to assemble a series of, what 35 I call, dry asymmetric cells and place the series in the receiving circuit; and in Fig. 2, the one asymmetric cell is replaced by a number of such cells connected in series as to each other. In testing this arrangement, I 40 have found that it is best to have the film of oxid on the aluminium plates inforced and not to make too rigid connections between the parts 5 and the parts 4.

I have stated above, that I had very good 45 results from an asymmetric cell comprising, as electrodes, an oxidized aluminium and a non-oxidized platinum; but I will state right here that instead of the aluminium, heavily oxidized iron may be substituted. 50 To produce a dry asymmetric cell, it is necessary that the two electrodes should be separated from each other, preferably by a heavy film of oxid of at least one of these metals; that is, this oxid film should be of comparatively 55 high resistance to the passage of an impulse in one direction, but should allow

the passage of an impulse in opposite direction.

The best results I have obtained were, when the two electrodes were of dissimilar 60 metal and where the oxid of one of these metals offered a very high resistance to the passage of the received impulses of one direction.

In all the figures, 15 designates the film of 65 oxid on the surface of the metal proper, and, as said above, different metals may be employed, but I prefer to use platinum as one electrode and aluminium as the second of said electrodes. 70

Having now described my invention, what I claim as new and desire to secure by Letters Patent is:

1. A detector for electro-magnetic waves comprising two series of metallic plates, the 75 surface of one series provided with an oxid, the surface of the second series in its metallic state, the plates of one series alternating with the plates of the second series; a plate of one series connected to one terminal of the 80 incoming circuit and a plate of the second series connected to the other terminal and means operatively related to said two series to translate the incoming impulses.

2. In wireless telegraphy, a detector comprising 85 a series of metallic plates in loose contact with each other, part of said plates provided with oxidized surface and the surface of part of said plates in its metallic state; a plate with oxidized surface alternating with 90 a plate the surface of which is metallic, a ground connection for one of said plates and an antenna for the other of said plates and a recorder shunting all of said plates.

3. In wireless telegraphy, a detector comprising 95 two series of metallic plates, the surface of one series oxidized, the surface of the other series in its metallic state; the plates of one series intervening between the plates of the second series, an antenna connected to 100 a plate of one series and a ground connected with a plate of the second series, and means to translate the incoming impulses, said means comprising a shunt around both series of plates and a translating device in 105 said shunt.

In testimony whereof I affix my signature in presence of two witnesses.

ISIDOR KITSEE.
